ADJUSTABLE SHELF

Filed Dec. 29, 1922

Inventor:
RICHARD B. CHAPMAN
by Hazardous Miller
Attorneys

Patented Mar. 11, 1924.

UNITED STATES PATENT OFFICE.

RICHARD B. CHAPMAN, OF SANTA BARBARA, CALIFORNIA, ASSIGNOR OF ONE-HALF
TO BEVERLY C. STEPHENS, OF LOS ANGELES, CALIFORNIA.

ADJUSTABLE SHELF.

Application filed December 29, 1922. Serial No. 609,671.

To all whom it may concern:

Be it known that I, RICHARD B. CHAPMAN, a citizen of the United States, residing at Santa Barbara, in the county of Santa Barbara and State of California, have invented new and useful Improvements in Adjustable Shelves, of which the following is a specification.

This invention relates to automobiles and 10 more particularly to receptacles for the convenient carrying and supporting of various articles and impedimenta.

It is an object of the invention to provide means adapted to be arranged in a normally 15 concealed position in front of the usual instrument board and behind the usual dash-board of a motor vehicle body. Another object is to provide a receptacle which may be readily withdrawn from a concealed position 20 into a convenient position for access, and where it will be arranged in exposed position in front of the driver and adjacent to the inner face of the instrument board.

Other objects and advantages will be made 25 manifest in the following specification of an embodiment of the invention illustrated in the accompanying drawings, wherein—

Figure 1 is a side elevation of a portion 30 of the body of an automobile, the near side of which is broken away.

Fig. 2 is a plan of the attachment.

Fig. 3 is a bottom plan view of the attachment.

The invention is shown as adapted to a 35 conventional form of automobile body having a dash-board 2 under the hood H and back of the dash-board is an instrument board 3. The spacing of the dash-board and the instrument board 3 provides a considerable 40 storage space not ordinarily utilized, and my present invention includes, in this form, a swinging element or shelf 5 which may be connected by a spring hinge 6 at one end to the inner face of the dash-board.

2. The swinging shelf is thus normally 45 swung upwardly by its spring hinge and is of such length that its rear end can swing up against the back of the instrument board.

3. The shelf 5 may be of any length and 50 width and upon it is slidably arranged a suitable number of receptacles or receivers. In the present case a receiver, in the form of a covered box 7, is slidably mounted on the shelf-like member 5.

55 Any suitable form of sliding construction

may be employed and is here shown as consisting of a pair of parallel strips 8 extending along side edges of the swinging shelf. 5. The side strips 8 are cross connected underneath the shelf 5 by connecting bars 9 and are cross connected by a top plate 10 forming a substantial and practical and at the same time light carrier, whereby the receptacle or box 7 may be shifted from a concealed position in front of the instrument board to an accessible and exposed position on the inner face of the instrument board in front of the driver of the automobile.

To provide for ready adjustment and mounting of the device upon vehicles of 70 various dimensions and forms of construction, the rear end of the swinging element or shelf 5 is shown as slotted at 5^a to receive clamp screws 12 which may be screwed into a leaf or base part 15 connected to the 75 hinge 6.

From the above it will be seen that I have provided an extremely simple, practicable, inexpensive, light and readily adjustable receptacle which may be quickly 80 moved to a concealed position in front of an instrument board or withdrawn to an exposed position at the inner face of the instrument board.

Further embodiments, modifications and 85 changes may be resorted to within the spirit of the invention as here claimed.

What is claimed is:

1. In combination with structural elements of an automobile including a dash 90 board and an instrument board mounted behind the upper part of the dash board and spaced therefrom, a bracket secured to the dash board, a shelf-like element pivoted to the bracket, a spring for holding the shelf-like element upwardly against the bottom of the instrument board, and a receptacle slidably mounted upon the element so as to be moved forwardly and swung upwardly in front of the instrument board and so as 100 to be moved downwardly and backwardly and swung upwardly behind the instrument board.

2. In combination with structural elements of an automobile including a dash 105 board and an instrument board, the instrument board being some distance behind the upper part of the dash board, a receptacle adjustably and yieldably mounted upon the dash board and adapted to be moved from 110

in front of the instrument board to the rear of the instrument board.

3. A carrying receptacle for attachment to automobiles comprising a shelf-like element having a spring hinge for attachment to the dash-board of an automobile, and a slidably mounted receptacle on said shelf-like element, whereby the shelf-like element

is adapted to be depressed to permit the receptacle to be shifted from a concealed position on one side of the instrument board to an exposed accessible position at the inner front of the instrument board. 10

In testimony whereof I have signed my name to this specification.

RICHARD B. CHAPMAN.
